CLAIM

The ornamental design for a fastener positioning device, as shown and described.

DESCRIPTION

FIG. 1 is an upper perspective view of the fastener positioning device embodying the new design;

FIG. 2 is a front view thereof;

FIG. 3 is a rear view thereof;

FIG. 4 is a right side view thereof, the left side being a mirror view thereof;

FIG. 5 is a top view thereof; and,

FIG. 6 is a bottom view thereof.

The evenly spaced broken lines rendered in FIG. 1 illustrates the environment of the claimed design and forms no part thereof. The dot-dot-dash broken lines in the drawings define the bounds of the claim and form no part thereof.
